US00D925488S

(12) **United States Design Patent** (10) **Patent No.:** **US D925,488 S**
Pedersen (45) **Date of Patent:** **** Jul. 20, 2021**

(54) HEADSET FOR TELEPHONE AND COMMUNICATION EQUIPMENT	D286,874 S 11/1986 Bertagna
(71) Applicant: GN AUDIO A/S , Ballerup (DK)	D288,299 S * 2/1987 Mark D10/40
(72) Inventor: Rasmus Trudslev Pedersen , Ballerup (DK)	D291,198 S 8/1987 Bellini
(73) Assignee: GN AUDIO A/S , Ballerup (DK)	4,899,135 A * 2/1990 Ghahariiran G08B 21/0227 340/539.1
(**) Term: 15 Years	5,018,599 A 5/1991 Dohi
(21) Appl. No.: 29/732,363	D318,053 S 7/1991 Ludeke et al.
(22) Filed: Apr. 23, 2020	D337,116 S 7/1993 Hattori
	D344,730 S 3/1994 Gattey et al.
	D345,163 S 3/1994 Yamatogi

(57)

CLAIM

The ornamental design for a headset for telephone and communication equipment, as shown and described.

DESCRIPTION

FIG. 1 is a front view of a headset for telephone and communication showing the new design.

FIG. 2 is bottom plan view of FIG. 1 thereof.

FIG. 3 is a top plan view of FIG. 1 thereof.

FIG. 4 is a right side plan view of FIG. 1 thereof.

FIG. 5 is a left side plan view of FIG. 1 thereof.

FIG. 6 is a rear plan view of FIG. 1 thereof; and,

FIG. 7 is a front perspective view of FIG. 1 thereof.

The features shown in broken lines depict environmental subject matter only and form no part of the claimed design.

1 Claim, 7 Drawing Sheets# US D925,488 S
